METHOD OF SETTING DRILLABLE LINERS
IN WELLS

Elwin B. Hall and Arthur L. Armentrout, Los Angeles, Calif., assignors, by direct and mesne assignments, to Security Engineering Co. Inc., a corporation of California

Application April 17, 1939, Serial No. 268,306

8 Claims. (Cl. 166—1)

This invention relates to a method of setting readily drillable liners in wells and may be considered as a continuation in part of the subject matter disclosed in our copending application 5 entitled Drillable well liner, Serial No. 185,530, filed January 18, 1938, now Patent No. 2,155,129, granted April 18, 1939.

An object of the invention is to provide a novel method of setting a readily drillable well liner in a well. In the conventional well the casing is formed of steel. As disclosed in our copending application above referred to, a highly satisfactory liner formed of certain types of aluminum alloys may be set in the well so as to extend 10 downwardly below the casing and will resist corrosion by ordinary fluids under the conditions that may be normally encountered in oil wells. Such liners possess the properties of being readily 15 drillable by conventional well drilling equipment and have a sufficiently low specific 20 gravity so that the cuttings may be readily flushed out of the well by the circulation fluid. Consequently, by the use of such a liner, whenever it is desired to remove the liner for any purpose, as for example deepening the 25 well, the liner may be readily drilled up and the cuttings flushed out.

With the liner being formed of a metal unlike that of the steel of the casing and with the liner in contact with the casing a type of galvanic action is set up between these contacting unlike 30 metals immersed in the oil well fluid. It sometimes also occurs that currents may be induced or imposed so that a form of electrolytic action 35 takes place. It is an object of the present invention to provide a method of setting liners in a well which contemplates the use of a readily 40 drillable liner formed of a material unlike that of the steel casing wherein the liner is set in such a manner as to avoid the setting up of this 45 galvanic or electrolytic action. Inasmuch as the liner itself is readily drillable the invention contemplates cementing the upper end of the liner in place without physical contact with the steel 50 casing. The presence of the cement does not interfere with the drilling up of the liner when occasion requires, and the surrounding body of cement contributes to the formation of a cement seal isolating water-bearing sands or formations from the oil or production zone.

With the foregoing and other objects in view, which will be made manifest in the following detailed description and specifically pointed out in the appended claims, reference is had to the accompanying drawings for an illustrative embodiment of the invention, wherein:

Figure 1 is a vertical section through the lower portion of a well illustrating the casing as having been cemented in place and illustrating the liner as having been run into the well to the desired 60 position;

Fig. 2 is a view similar to Fig. 1, but illustrating the manner in which the liner is set in position by means of cement;

Fig. 3 is a view similar to Fig. 1 illustrating the cementing operation as having been completed;

Fig. 4 is a view similar to Fig. 3 illustrating the completion of the operation for setting the liner;

Referring to the accompanying drawings wherein similar reference characters designate 10 similar parts throughout, the reference character 10 indicates a steel casing which may have been cemented in place in a well as by cement 11. The liner is generally designated at 12 formed of a plurality of tubular sections of readily 15 drillable material. The material employed is preferably one of the alloys disclosed in our copending application inasmuch as those alloys possess the properties of required strength, corrosion resistance, drillability, and low specific 20 gravity. However, in the performance of this invention other materials may be employed, either metallic or non-metallic, and if metallic, aluminum alloys other than those disclosed in our copending application may be employed if resistance 25 to corrosion is sacrificed.

The liner illustrated has an upper imperforate section 13 and lower perforated sections 14. At the bottom of the imperforate section there is a collar 15 provided with cementing ports 16 and with a drillable baffle plate 17 in which is seated a cementing valve 18. The cementing valve may be of any desired or preferred construction, the one illustrated being so designed as to permit upward flow through the liner while the liner is being lowered into the well but to prevent downward flow past the baffle plate during cementing operations. At the top of the liner there is an adapter 19 also formed of readily drillable material. The liner is optionally but preferably equipped with a cement basket 20 immediately below collar 15 which will prevent cement from being forced downwardly about the liner therebelow. The liner is lowered into the well by means of a run-in string of pipe 21 preferably equipped with a setting tool 22 which is releasably connected such as by left-hand threads to the adapter 19. A tube 23 extends downwardly from the run-in string of pipe into the liner and serves to discharge cement therein immediately above collar 15. This tube is preferably equipped with packing means 24 closely fitting the interior of the liner to prevent the escape of cement upwardly therewith. The adapter 19 is slightly smaller than the interior of the casing, the intention being that when the liner is set the adapter will be out of contact with the casing. However, as the adapter occupies a large portion of the interior of the casing it serves to some extent to confine the cement between the adapter and the cement basket 20.

With the liner installed in the well by means of the run-in string of pipe 21, as shown in Fig. 1, cement is then forced downwardly through the run-in string of pipe and is discharged therefrom above the cementing valve 18. The cement is forced outwardly through the ports 16 and as it cannot flow downwardly past the cement basket 20 it flows upwardly completely filling the space between the upper portion of the liner and the well walls and filling the space between the top of the liner and the bottom of the casing below adapter 19. When the cement is completely discharged the run-in string of pipe is rotated to disconnect the setting tool 22 therefrom and the run-in string of pipe is pulled upwardly a short distance and circulation therethrough is reestablished.

As the packing means 24 is pulled out of the liner and circulation fluid is discharged therethrough, the top of the liner is effectively cleaned of cement. Circulation is continued to wash away excess cement that may be in the casing above the adapter after which the run-in string of pipe is withdrawn and the cement is allowed to set leaving the well in the condition as shown in Fig. 3. In this condition, it will be noted that there is a small amount of cement in the liner immediately above the cementing valve 18. A bit 25 is then lowered into the well by means of a drill pipe 26 and the cement remaining in the liner, the cementing valve 18, and the baffle plate 17 is drilled out after which the well is in condition to be placed on production.

It will be noted that by this method of setting a liner that if for any reason it should be desired to remove the liner, the adapter, liner, cement basket, and the surrounding cement indicated at 27 can be readily drilled out leaving the well in excellent condition for further operations. While the liner remains set in the well, it will be noted that there is no contact or electrical connection between the liner and the casing. Consequently, even though the liner may be of a metal unlike that of the steel casing, and would be such that either a galvanic action or an electrolytic action might take place under certain conditions, the interposed body of cement prevents the presence of an electrolyte between the casing and the liner. In addition, the cement body at 27 cooperates with the cement 11 in maintaining a cement seal shutting off communication between any upper water-bearing strata and the desired oil or producing zone.

The term "cement" as used herein is intended to include any substance used for cementing casings in wells, but in order to gain the advantage of preventing galvanic action or electrolytic action between the liner and the casing the cement employed should either be a non-conductor of electricity or an extremely poor one, and should be impervious to conducting fluids or liquids that might constitute an electrolyte between the liner and casing.

From the above-described construction and method it will be appreciated that an improved method for setting liners in wells is developed wherein, if the liner is formed of metal unlike that of the casing which might, under certain conditions, be conducive to the setting up of the galvanic or electrolytic action, that the liner is set

in such a manner that the galvanic or electrolytic action in fact will not be set up. At the same time, however, it is possible at all times to readily remove the liner but as long as the liner remains in the well it is firmly positioned by cement which contributes to effecting a water shutoff. 5

Various changes may be made in the details of construction without departing from the spirit or scope of the invention as defined by the appended claims. 10

We claim:

1. The method of setting a readily drillable liner in a well which includes forcing cement into the space between that portion of the liner that extends up into the casing and the casing and 15 allowing the cement to set.

2. The method of setting in a well a readily drillable liner formed of a metal unlike that of the metal of the casing so as to retard or prevent galvanic or electrolytic action that might take 20 place between the unlike metals, which method comprises cementing between the top of the liner and the bottom of the casing.

3. The method of setting in a well a readily drillable liner formed of a metal unlike that of 25 the metal of the casing so as to retard or prevent galvanic or electrolytic action that might take place between the unlike metals, which method comprises cementing between the top of the liner and the bottom of the casing in such a manner 30 that the liner will be held out of contact with the casing.

4. A well liner formed of readily drillable metal having a readily drillable cementing valve therein 35 adjacent the upper portion thereof, ports in the walls of the liner above the cementing valve and a cement basket on the exterior of the liner below the ports.

5. A well liner formed of readily drillable material having a readily drillable cementing valve 40 therein adjacent the upper portion thereof, and ports in the walls of the liner above the cementing valve.

6. A well liner formed of readily drillable metal having a readily drillable cementing valve therein 45 adjacent the upper portion thereof, and ports in the walls of the liner above the cementing valve.

7. The method of setting in a well a readily drillable liner formed of a metal unlike that of the metal of the casing so as to retard or prevent 50 galvanic or electrolytic action that might take place between the unlike metals which method comprises cementing between the upper portion of the liner and the well walls and having the cement extend up into the space between the top of the liner and the bottom of the casing.

8. The method of setting in a well a readily drillable liner formed of a metal unlike that of the metal of the casing so as to retard or prevent galvanic or electrolytic action that might take 60 place between the unlike metals which method comprises cementing between the upper portion of the liner and the well walls and having the cement extend up into the space between the top of the liner and the bottom of the casing so as 65 to occupy all of the space between the top of the liner and the bottom of the casing.

ELWIN B. HALL.

ARTHUR L. ARMENTROUT. 70
